UNITED STATES PATENT OFFICE
VENT-PIPE PROTECTOR

HENRY ROBINETT AND CHARLES W. CODY, OF LONG BEACH, CALIFORNIA.

VENT-PIPE PROTECTOR.

1,166,005.

Specification of Letters Patent. Patented Dec. 28, 1915.

Application filed December 5, 1914. Serial No. 875,659.

To all whom it may concern:

Be it known that we, HENRY ROBINETT and CHARLES W. CODY, citizens of the United States, residing at Long Beach, in the county of Los Angeles and State of California, have invented a new and useful Vent-Pipe Protector, of which the following is a specification.

One of the objects of this invention is to provide a vent pipe fitting or protector to be attached to the upper end of a vent pipe or to any other suitable and necessary part thereof, and so constructed as to exclude objects from said pipe but allow a free upward 15 or downward passage of air and gas.

Another object is to check or eliminate back draft in vent pipes.

In the drawings: Figure 1 is a side elevation of the protector; Fig. 2 is a vertical, 20 longitudinal, sectional view taken on a plane of line 2—2 of Fig. 3; Fig. 3 is a top plan view of the protector; Fig. 4 is a horizontal section taken on a plane of line 4—4 of Fig. 2. Fig. 5 is a transverse sectional view 25 showing a modified form of guard member.

Referring in detail to the drawings by numerals: 1 designates as an entirety the casting forming the fitting or protector.

30 The casting comprises a preferably cylindrical body or barrel 2 having a passage 3 extending entirely therethrough. The barrel may be of any suitable length and diameter and is integrally connected on one 35 side adjacent its lower end to an offset portion or elbow 4 having its upper side extending aslant upward toward the barrel to form a deflecting surface, said elbow being of an enlarged diameter adjacent its lower 40 end to form a socket or chamber 5 which receives the vent pipe 6. It will be understood that the elbow may also be made of any desired size and that the pocket or chamber 5 may be varied in size to meet 45 any requirement. Within the elbow and extending entirely thereacross at the juncture of the elbow with the barrel is a guard or lug 7 which projects upwardly into the elbow and which has its outer face 8 inclined 50 downwardly and outwardly. This guard

which appears substantially triangular in cross section makes it impossible for an object to be thrust into the vent pipe through the top of the barrel and the inclined face 8 slopes upward toward the deflecting surface 55 of the elbow 4 so that air blowing into the lower end of the barrel will be deflected upward against the deflecting surface of the elbow and will then be deflected upward and outward by said deflecting surface, thus 60 insuring against down draft in the vent pipe. The barrel is formed in one side adjacent its lower end with an opening 9 to establish communication with the passage 10 of the elbow. This elbow extends outwardly from the barrel and then downwardly below the bottom of the barrel as clearly shown. As a further guard means for the fitting we provide the cross bars 11 and 12 which extend across the interior of 70 the barrel 2 near the upper and lower ends respectively. These bars are sufficient to prevent any one reaching into the fitting and dropping objects into the vent pipe. In larger fittings such as illustrated in Fig. 5, 75 we find it advantageous to employ in place of the single cross bars, such as illustrated in Figs. 2, 3 and 4, the cross construction 13 shown.

14 is a set screw to secure the fitting to the 80 vent pipe 6. It will of course be understood that any other means for securing the fitting in position may be employed.

While we have shown and described the preferred embodiment of our invention, it is 85 to be understood that we do not wish to be limited to this exact construction, but may make such changes in design, proportion and arrangement of parts as may occur from time to time, and as will come within the 90 scope and spirit of the invention as claimed.

What we claim is:

A fitting of the character described comprising a vertical barrel having an opening extending therethrough, an elbow formed 95 on one side of said barrel adjacent its lower end and communicating with the interior thereof, said elbow extending outwardly and downwardly from its point of contact with the barrel and having its upper side extend- 100

ing aslant upward toward the barrel to form a deflecting surface, and a guard formed within the elbow, said guard having its outer face inclined downwardly toward the barrel and sloping upwardly toward the deflecting surface of the elbow.

5 In testimony whereof, we have hereunto

set our hands at Los Angeles, California, this 27th day of November, 1914.

HENRY ROBINETT.
CHARLES W. CODY.

In presence of—

LORA M. BOWERS,
ANNA F. SCHMIDTBAUER.
